(57) **CLAIM**

The ornamental design for a cover for an adhesive roller, as shown and described.

DESCRIPTION

FIG. 1 is a top perspective view of a cover for an adhesive roller showing our new design.

FIG. 2 is a bottom perspective view of the cover shown in FIG. 1.

FIG. 3 is a front view of the cover shown in FIG. 1.

FIG. 4 is a bottom view of the cover shown in FIG. 1.

FIG. 5 is a top view of the cover shown in FIG. 1.

FIG. 6 is a left view of the cover shown in FIG. 1.

FIG. 7 is a right view of the cover shown in FIG. 1.

FIG. 8 is a top perspective view of an alternate embodiment of a cover for an adhesive roller.

FIG. 9 is a bottom view of the cover of FIG. 8.

FIG. 10 is a front view of the cover of FIG. 8.

FIG. 11 is a bottom view of the cover of FIG. 8.

FIG. 12 is a top view of the cover of FIG. 8.

FIG. 13 is a left view of the cover of FIG. 8; and,

FIG. 14 is a right view of the cover of FIG. 8.

The broken line showing of environmental structure in FIGS. 1-7 is for illustrative purposes only and forms no part of the claimed design.
